UNITED STATES PATENT OFFICE

2,373,053

LATCH CONSTRUCTION

Albert J. Rhodes, Pontiac, Mich., assignor to
American Forging & Socket Company, Pontiac,
Mich., a corporation of Michigan

Original application May 23, 1940, Serial No.
336,782, now Patent No. 2,302,957, dated Novem-
ber 24, 1942. Divided and this application Sep-
tember 14, 1942, Serial No. 458,183

3 Claims. (Cl. 292—346)

This invention relates to latch mechanisms and equivalent holding devices, being particularly, although not exclusively, adapted for use in latching the hoods of motor vehicles.

An important object of the invention is to provide an improved and simplified hood latch, incorporating safety catch mechanism in conjunction with a main latch, the safety catch mechanism being automatically called into play upon release of the main catch, and preventing complete release of the hood, or other held portions, save when deliberately manipulated in a manner which is only possible when the vehicle is at rest.

Another object of the invention is to arrange a shield between the open grille of the motor vehicle and the movable parts of my improved latch mechanism, this shield being positioned so as to prevent manipulation of the latch mechanism by an implement thrust through the grille without, however, impairing the movements of the movable latch parts.

Other objects and advantages will be apparent from the following description, wherein reference is made to the accompanying drawings illustrating a preferred embodiment of my invention, and wherein similar reference numerals designate similar parts throughout the several views.

The present application is a division of my co-pending application Serial No. 336,782, filed May 23, 1940, now Letters Patent No. 2,302,957, issued November 24, 1942.

In the drawings:

Figure 1 is a somewhat diagrammatic side elevational view of the front portion of the hood of a motor vehicle provided with a hood latching means constructed in accordance with the present invention, portions of the hood and radiator grille being broken away to disclose the positioning of the latch assembly.

Figure 2 is a plan view of that portion of the latch mechanism which is carried by the fixed part of the vehicle structure, the lid or bonnet section being raised.

Figure 3 is a vertical longitudinal central section of the latch mechanism and adjacent supporting portions of the vehicle structure, showing the parts in the positions they occupy when the lid is fully closed and latched.

Figure 4 is a sectional view similar to Figure 3 on the line 4—4 of Figure 2, but showing the main catch released and the safety catch blocking full opening movement of the lid.

Figure 5 is a vertical section taken substantially

on the line 5—5 of Figure 2, and looking in the direction of the arrows.

Figure 6 is a plan view of that portion of the latch assembly which is carried by the lid section showing the same removed from the lid.

Fig. 7 is a detail perspective view showing a preferred form of mounting the inner edge of the shield.

Referring now to the drawings, it will be seen that a vehicle body having a front engine-enclosing hood of more or less conventional arrangement is illustrated in Figure 1. The fixed hood portion 10 forms the main enclosure for the engine compartment, which is accessible through a lid or bonnet 12, hinged to the vehicle at its back edge and adapted to be lifted from the front.

A gusset plate 15, mounted within the nose of the lid section, and serving also as a reinforcement, carries a relatively heavy stud 17 projecting downwardly therefrom, riveted or otherwise secured in place. The portion of the stud which extends through the gusset plate is preferably flattened upon at least one side, to lock it against turning. The lower end of the stud is threaded, and carries a substantially conic head 20 forming a keeper. The keeper is threaded upon the stud and adapted to be locked against turning by means of a set screw 21. The substantially conic shape of the keeper will be seen to provide a shoulder, 22, at right angles to the stud, while its threaded mounting allows adjustment thereof, simply by loosening set screw 21 to permit rotation of the keeper.

To the under side of a cooperating plate 30, secured to the fixed portion of the vehicle structure, as by bolts 31, and apertured as at 32 in position to permit the keeper head 20 to project therethrough, is pivoted a swinging sheet metal bolt 25. Bolt 25 is normally drawn into locked overengagement with the shoulder 22 of the keeper by means of a spring 33. This mechanism is positioned forwardly of the radiator 24 and behind the front grille 50. Bolt 25 would accordingly be accessible by means of an implement thrust through the grille, were it not guarded by the shield 49.

A spring 35, encircling stud 17, resists closing movement of the lid, and lifts the same sufficiently to free the keeper head 20 from the bolt 25 whenever the latter is released. Spring 35 is positioned by and bears against an inverted cup 37, slidably upon the stud. The lower edge of the cup is flanged to form a seat for the spring, and such flange, being too large to pass through

the opening 32, serves as an abutment to restrain the lower end of the spring and cause the same to be compressed as the lid is pressed downwardly to force the keeper through the opening 32. An opening 39 is formed in cup 37 to permit a screw driver to be thrust therethrough into engagement with the set screw 21, and the lower extremity of the keeper head 20 is also slotted, as indicated at 23, to allow the same to be conveniently turned when the set screw is loosened, as well as rounded to assist camming the bolt. Cup 37 is rotatable upon the stud, to permit alignment of the opening 39 with set screw 21.

A lug 40 is turned up from one edge of the bolt 25, and projects through a slot 42 in plate 30. A flexible cable 44, attached to the lug and connected to a conveniently positioned button 45 located upon the instrument panel 47 of the vehicle, enables the bolt 25 to be released at will.

The shield 49 is formed of sheet metal and secured to the plate 30, underlying the bolt 25 and spring 33 to prevent picking the latch by means of an implement thrust through the front grille 50.

As best shown in Figs. 2 and 5, the shield 49 is arranged between the keeper 20 and one side of the grille, and is herein shown as substantially triangular in contour with its corners secured to the underside of the supporting plate 30, the central portion of the shield 49 being depressed to form a housing for the free end of the pivoted latch bolt 25 and cooperating elements. This depressed portion of the shield is closed at the front and side adjacent the grille to prevent ingress of an implement thrust through the grille into contact with the latch bolt 25 but is open at the rear and opposite side to permit desired movements of the latch bolt 25 when the button 45 is pulled to open the bonnet 12. These open rear and side portions of the shield 49 are so protected by the radiator and other latch parts arranged at the center of the vehicle that the latch bolt 25 cannot be manipulated therethrough. Two of the bolts 31 passing through elongated slots in horizontal flanges bent outwardly from the upper edges of the front and outer side walls of shield 49 are utilized in securing the shield in position. (Note Fig. 2.) The other corner of the triangular shield is preferably secured to plate 30 substantially in the manner shown in Fig. 7. A flange 49^a is formed with a pair of spaced upstanding tabs 49^b, which are arranged to pass through slots in plate 30 and then are bent over into contact with plate 30 to suspend the shield. An elongated aperture 49^c is pierced in the side wall of shield 49 below flange 49^a (Fig. 7), and the side walls of such aperture may serve as stops to limit the swinging movement of bolt 25.

I am aware that the invention may be embodied in other specific forms without departing from the spirit or essential attributes thereof, and I therefore desire the present embodiment to be considered in all respects as illus-

trative and not restrictive; reference being had to the appended claims rather than to the foregoing description to indicate the scope of the invention.

5 I claim:

1. Hood latching means adapted to hold in closed position the bonnet section of a motor vehicle body of that type having a radiator and a grille spacedly disposed in front of the same, and having a bonnet hinged at its rear extremity and overlying the space between the radiator and grille, comprising a support arranged between said grille and radiator and near the top of the space therebetween, a holding element carried by said support and movable to and from holding engagement with a part carried by the bonnet when the latter is closed, and shielding means underlying said holding element and projecting laterally between it and the adjacent side of said grille into position to prevent manipulation of said holding element by means of an implement thrust through the grille.

2. Hood latching means adapted to hold in closed position the bonnet section of a motor vehicle body of that type having a radiator and a grille spacedly disposed in front of the same, and having a bonnet hinged at its rear extremity and overlying the space between the radiator and grille, comprising a support arranged between said grille and radiator and near the top of the space therebetween, a holding element carried by said support and movable to and from holding engagement with a part carried by the bonnet when the latter is closed, and shielding means underlying said holding element and preventing manipulation thereof by means of an implement thrust through the grille, said shielding means comprising a plate secured at its edges to said support and having a depressed portion extending below and enclosing the portion of the holding element nearest said grille.

3. Hood latching means adapted to hold in closed position the bonnet section of a motor vehicle body of that type having a radiator and a curved grille, spacedly disposed in front of the radiator with its sides adjacent the sides of the radiator, and having a bonnet hinged at its rear extremity and overlying the space between the radiator and grille, comprising a support arranged between said grille and radiator and near the top of the space therebetween, a holding element carried by said support and movable to and from holding engagement with a part carried by the bonnet when the latter is closed, said holding element having one extremity pivotally secured adjacent the center of the radiator and its free extremity extending toward a curved side of the grille, and shielding means underlying and partially enclosing the free extremity of said holding element whereby manipulation thereof by means of an implement thrust through the grille is prevented.

ALBERT J. RHODES.
